UNITED STATES PATENT OFFICE

93,027

DESIGN FOR A MEMORIAL CLOCKCASE

Joseph Lesser, Binghamton, N. Y.

Application July 22, 1933, Serial No. 48,793

Term of patent 3½ years

To all whom it may concern:

Be it known, that I, JOSEPH LESSER, a citizen of the United States, residing at Binghamton, in the county of Broome and State of New York, have invented a new, original, and ornamental Design for Memorial Clock Cases, of which the following is a specification, reference being had to the accompanying drawing, forming a part thereof, in which

Fig. 1 is a front elevation,

Fig. 2 is a rear elevation, and
Fig. 3 is a side elevation.

I claim:

The ornamental design for a memorial clock case substantially as shown

In testimony whereof I have affixed my signature.

JOSEPH LESSER.
